UNITED STATES PATENT OFFICE.

CARL KINSLEY, OF NEW YORK, N. Y.

METHOD OF AND APPARATUS FOR TRANSLATING SIGNAL VARIATIONS.

Application filed March 29, 1920, Serial No. 369,616. Renewed October 26, 1923.

To all whom it may concern:

Be it known that I, CARL KINSLEY, a citizen of the United States, and resident of New York city, in the county of New York and State of New York, have invented certain new and useful Improvements in Methods of and Apparatus for Translating Signal Variations, of which the following is a specification.

10 My present invention is primarily intended for translating electrical variations of the kind which are used in signalling by so-called wireless or radio-telegraphy but it is applicable for use in other analogous relations and in fact in any relation where its functioning may prove useful or desirable.

My invention includes as an essential feature the application of the electrical variations to magnetize and thereby set up longitudinal vibrations in a bar of magnetic material, preferably pure soft iron. As is well known, an iron bar lengthens when magnetized and contracts upon decrease or reversal of magnetism and my invention contemplates the clamping of such a bar at one end leaving the other end free so that all such expansion is effective in producing longitudinal movement of the free end of the bar. This longitudinal movement of the free end of the bar is utilized in any desired way to produce an indication or effect.

One of the most desirable ways is to apply the motion at the free end of the bar to precipitate bushing of a sensitive jet. My invention was devised primarily for use in connection with the cool air jet and sensitive resistance indicator set forth in the application of Ray E. Hall, Serial No. 301,010, filed May 31st, 1919, which has now become Patent No. 1,378,345, dated May 17, 1921, but it may be employed in connection with the jet actuated apparatus set forth in his earlier Patents Nos. 1,160,072 and 1,205,530, and it is capable of use in connection with a sensitive flame.

While such employment of the magnetizable rod in combination with a sensitive jet or flame has peculiar advantages, the longitudinal movement of the free end of the rod may be utilized to produce an indication in other ways and my invention is not to be considered as limited except in so far as concerns claims in which the above mentioned combination is specified.

55 Preferably the received variations are

periodic and of a definite frequency and the longitudinal vibrating bar of magnetic material preferably has a physical length which is a quarter wave length or an odd multiple of a quarter wave length of a sound wave of said frequency when propagated in iron.

In such case the fixed end of the bar becomes a node and the free end of the bar a vent of a longitudinal resonant vibration built up by the rhythmic elongations and retractions at the free end of the bar coinciding in phase with the longitudinal vibrations reflected from the fixed nodal end of the bar. The same resonance effects may be produced when the bar is an odd multiple of a quarter wave length provided its fixed point is a node and the point utilized to produce the indication is a vent of the resonant longitudinal vibration of the rod. The rod of quarter wave length is preferable, however, because the mass to be set in vibration is smaller so that full resonant vibration requires less time and energy when the energizing impulses cease and the vibration dies out more promptly.

Where the magnetic rod is employed in connection with a sensitive jet my invention includes the further feature of applying the motion of the free end of the rod through a conical tip carried by the free end of the rod and encircling the jet.

When the invention is used for translating radio signals, the received waves may be applied directly for translation provided the wave length employed is sufficiently long and the frequency low enough for effective electromagnetic effect on iron. If desired, however, the variations to be translated may be of lower frequency than the radio waves and such lower frequencies may be produced in any desired way, as, for instance, by superposing a locally originated frequency upon the received waves to produce an electrical heterodyne, or by utilizing a group frequency in connection with any of the well known amplifiers which produce a single electrical impulse or variation in response to a whole train of radio waves.

The above and other features of my invention may be more fully understood from the following description in connection with the accompanying drawings in which—

Figure 1 is a diagrammatic view of one embodiment of my invention and means for

energizing the device directly by waves of radio frequency; and

Figure 2 is a similar view showing means for energizing the device by amplified variations which may be of less than radio frequency.

In these drawings 1 is the magnetizable rod fixed at one point by clamp 2 and screw 3 which are rigidly secured to a suitable support 4. The free end of the rod is encircled by an electromagnetic coil 5. Preferably the coil 5 is arranged so that its center is at or near the end of the rod. This tends to locate the magnetic pole at the end of the rod and whatever solenoidal pull the coil has will take effect longitudinally of the rod.

On the end of the rod 1 is a light tubular extension 6 preferably of non-magnetic material having rigidly secured to the end thereof, the cone 7 which encircles the outlet of the sensitive jet 8.

This jet 8 is adjusted so as to be particularly sensitive to vibrations of the frequency of the magnetizing current variations so that longitudinal vibration of the rod, causing transverse movement of the cone 7, easily precipitates bushing of the jet. This bushing of the jet is intermittent and is of the same frequency as the variations in coil 5. Such intermittent bushing may be utilized to produce an indication, preferably according to the methods described in the Hall application and patents above mentioned.

In Figure 1, I have diagrammatically indicated the jet as normally discharging along the axis of a coil 10 of very fine wire which is normally kept hot by flow of current from battery 11. Bushing of the jet variably cools coil 10 thereby lowering its resistance and increasing the flow of current from the battery 11. These fluctuations of battery current flow are utilized to produce the desired indication or effect in an indicating device 12 which may be a telephone receiver, relay, recorder or other suitable device.

In Figure 1 the coil 5 is shown as energized directly by the received waves of a wireless telegraph system, operating at radio frequency and without the interposition of any amplifier or so-called detector. This is quite possible since the velocity of sound in steel or iron is about 5100 meters per second. A radio signal of say 15,000 meters wave length is available by means already well known in the art. Waves of this length have a frequency of about 20,000 per second. The length of an acoustic wave of this frequency when propagated in iron is 5100 meters which, divided by 20,000 frequency, equals .255 meter, or 25.5 centimeters. An iron rod one quarter such length would be 6 $\frac{1}{2}$ centimeters from the fixed nodal point to the vent

or point of maximum movement therof. In practice the actual length of the rod and its clamping point may be slightly varied above or below this length until the apparatus shows pronounced longitudinal vibratory resonance when energized by variations of 20,000 or other predetermined frequency.

The incoming radio waves energize aerial conductor 20, grounded at G and including transformer primary 21 and adjustable condenser 22 which may be tuned to the frequency of the received waves. Primary 21 energizes the secondary winding 23 in series with coil 5 and having in shunt relation thereto the adjustable tuning condenser 24.

My invention is not limited to such use in connection with unamplified waves, and I may employ a more common receiving apparatus as diagrammatically indicated in Figure 2.

In this figure the aerial receiving wire 20, the transformer primary coil 21 adjustable condenser 22, ground G and transformer secondary 23 and adjustable condenser 24 may be the same as before. Instead of leading the wires directly to coil 5, however, the received energy is applied to an audion or other amplifier. The hot wire loop 26 energized by battery 27 is connected to one side of the circuit and the grid 28 to the other side of the circuit. The plate is connected in series with battery 29 through coil 30. This coil may be the magnetizing coil 5. If desired, however, a second amplifying circuit 32 may be interposed by making the coil 30 the primary of a transformer having its secondary 31 in the second amplifying circuit. The battery fluctuations of this latter circuit may be applied through conductors 40, 41 to the coil 5.

In the arrangement shown in Figure 2, it will be observed that the amplifying devices are of a character which give increased battery flow for the entire duration of a wave train. Hence the trains must be broken up into groups succeeding each other at definite frequency so that the resulting battery fluctuations in the amplifier circuit will be of a frequency suitable for setting up the longitudinal vibrations of rod 1 so as to cause the desired breaking or bushing of the sensitive jet.

Where an amplifier or similar detector is used the variations in coil 5 are uni-directional fluctuations which do not reverse the polarity but only increase and decrease the magnetism of bar 1. Hence the frequency of the elongations of the bar, is the same as the frequency of the variations.

On the other hand, the arrangement shown in Figure 1 applies alternating current variations to the coil so that the magnetism is reversed twice for each complete wave, and the bar vibrations are double the fre-

frequency of the waves. Moreover, this frequency being necessarily high, the coil 5 and bar 1 should be designed so as to minimize the choking effect of inductance, 5 capacity and resistance. Such doubling of the frequency may be avoided by imparting a desired degree of normally continuous magnetism to the bar 1 so that the incoming alternating impulses will operate only 10 to increase and decrease such normal magnetism.

By predetermining the amount of such normally continuous magnetism the variations of magnetism may be made to have 15 a zero or any other desired value of magnetism as the lower limit. Similarly where unidirectional currents are used, they may operate wholly by demagnetizing instead of magnetizing the bar 1. The normal 20 continuous magnetic condition of the bar may be brought about in any of the ways well known in the art as by the use of a permanent magnet which may be of steel or by the use of a magnetizing coil where 25 iron is the material used.

Broadly considered, my invention is not limited to iron or steel as the magnetizable material since it is well known that cobalt and nickel are also magnetizable. The latter 30 metals shorten upon magnetization and lengthen upon de-magnetization, the reverse of what happens in the case of steel and iron, but change of length being a primary requisite of my invention, these or 35 other magnetizable metals or alloys are within the broad limits of my present invention.

From the above it will be evident to those skilled in the art that magnetization 40 and demagnetization as also shortening and lengthening may be full equivalents, and that the terms "magnetizable", "magnetize", etc. as used above and also in the following 45 claims should be construed accordingly.

45 I claim:

1. The method of translating electrical variations which consists in applying the same to magnetize a rod so as to cause longitudinal movement of a portion thereof 50 and applying said movement to reciprocate bushing of a sensitive jet and utilizing the latter to produce a sensible indication or effect.

2. The method of translating periodic electrical variations of definite frequency 55 which consists in applying the same to periodically magnetize an iron rod having a physical length equal to one quarter the length of an acoustic wave of said frequency when propagated in iron, to thereby cause 60 resonant longitudinal vibration and resultant movement at a free end thereof and utilizing such movement to produce a sensible indication or effect.

3. The method of translating periodic electrical variations of definite frequency which consists in applying the same to periodically magnetize an iron rod having a physical length equal to one quarter the length of an acoustic wave of said frequency 70 when propagated in iron, to thereby cause resonant longitudinal vibration and resultant movement at a free end thereof and applying said movement to precipitate bushing of a sensitive jet and utilizing the latter 75 to produce a sensible indication or effect.

4. A translating device for periodic variations of definite frequency, including a magnetizable rod having a physical length equal to one quarter the length of an acoustic 80 wave of said frequency when propagated in iron, and means for holding said rod fixed at one end and at the other end free for expansion and contraction, in combination with a magnetizing coil for said rod 85 and means for periodically energizing said coil.

5. A translating device for periodic variations of definite frequency, including a magnetizable rod having a physical length equal 90 to one quarter the length of an acoustic wave of said frequency when propagated in iron, and means for holding said rod fixed at one end and at the other end free for expansion and contraction, in combination 95 with a magnetizing coil for said rod and means for periodically energizing said coil at a rate synchronizing with and adapted to amplify longitudinal physical vibrations set up in said rod by the magnetizing 100 effect of said coil.

Signed at New York city, in the county of New York and State of New York this 5th day of March A. D. 1920.

CARL KINSLEY.
